UNITED STATES PATENT OFFICE.

GARROLD L. BAILEY, OF NEWARK, NEW JERSEY.

SOUND AMPLIFIER.

Application filed December 27, 1924. Serial No. 758,325.

This invention relates to devices for enhancing or increasing the volume of sound emanations, rendering audition more satisfactory, such devices being variously termed 5 sound amplifiers, loud speakers, resonators, horns, etcetera.

One of the features of the present invention is in the provision of an amplifier made wholly of wood, because of its resonant 10 properties, shaped in a novel and attractive form and so arranged internally that microphonic sound waves are propagated and eventually diffused with greatly increased resonance due to the sympathetic 15 vibrations of the structure.

Another object is to provide an amplifier in which the sound waves as received from their source, are directly through a channel of constantly increasing cross sectional area 20 to a point where they become separated into equal parts, each passing through chambers having resonating walls, to become combined into a perfectly synchronized union prior to their ejection into the atmosphere 25 with unusual sonorance and clarity.

These several aims and objects are accomplished by the novel construction and arrangement of parts hereinafter described and shown in the accompanying drawing, 30 forming a material part of this disclosure, and in which:—

Figure 1 is a perspective view of an embodiment of the invention, looking from its face.

Figure 2 is a front elevational view of the apparatus, with the face or front wall removed.

Figure 3 is a vertical sectional view taken on line 3—3 of Fig. 2.

Figure 4 is a transverse sectional view, taken in different planes as indicated by the line 4—4 of Fig. 2.

Stated in general terms the apparatus consists of a hollow, drum-shaped body, 45 mounted on a base containing the microphone, to which electrical connections lead from the sound source.

Except for the metallic microphone socket and a gauze-like fabric to prevent entrance 50 of dust and insects through the sound issuing openings at the front, all parts of the

device are constructed entirely of wood, the casing or body walls and partitions being preferably made of hardwood veneer, shaped as shown and held in place by 55 strong cement.

Referring more in detail to the drawing, the numeral 10 designates in general a base having a flat rectangular lower surface, parallel front and rear sides and ornamental 60 profiled ends which slope symmetrically to its concave upper surface 11.

A cylindrical band 12, of uniform width and thickness is fixed on the curved seat 11 and provided with an imperforate disc 13, 65 of corresponding diameter, at its back, a similar disc 14 being secured at the front, this front or cover disc having a generally ovoidal opening 15 in its lower portion, its bottom edge being substantially concentric 70 with the adjacent periphery of the disc.

This opening is for the emission of sound and is partially filled with ornamental fret work 16 of such fanciful design as may be preferred.

A lining, not shown, of any open meshed fabric may be applied to the inner side of the disc to prevent the entry of insects, dirt and the like, as will be readily understood.

An open recess 17 is formed centrally in 80 the bottom of the base 10 to receive a microphone, indicated at 18 in broken lines, the same being secured in a socket 19 extending from the recess 17 through the wall of the band 12 and an opening 20 in the rear 85 wall of the base admits the passage of conductors leading from the source of supply of sound to the microphone.

A tube 21, in the form of a reversed truncated pyramid, is arranged centrally 90 within the band 12, its smaller, open end enveloping the inner extending end of the socket 19, and its larger, upper end, expanded to fill the space between the discs 13 and 14, extends to a definite spaced distance 95 from the inner surface of the ring 12, at a point diametrically opposite the base, this distance being approximately equal to one-half the width of the tube end.

A substantially triangular abutment 22, 100 having two uniformly curved sides blending into the band 12, to which it is secured

transversely at the top, presents its acute edge directly over the open end of the tube 21 at its center.

Accurately curved thin partitions 23 extend between the discs 13 and 14, these partitions joining the upper edge of the tube 21 to extend downwardly slightly below its center, essentially constituting a circle, their lower ends being in contact with blocks 24 10 filling the space between the walls of the tube 21 and respective front and rear discs, but capable of vibrating and excluding the sound waves from the spaces enclosed by them, causing the sound waves to branch 15 oppositely.

A pair of opposed concavely curved filler blocks 26, connected with the sides of the tube 21, extend outwardly along the rear disc 13, from the ring elements 23 to the 20 band 12, to direct the sound waves outwardly through the opening 15, behind which they are located, and a central vertical strip 27 between the front of the tube and disc 14 completes the separation of sound.

It is to be noted that the angular edge 25 of the element 22 is arranged to bisect the tube 21, and its curved portions are so located with references to the lateral edges of the tube, at their juncture with the partitions 23, as to present ever increasing spaces for the sound waves over the half of the sectional area of the larger end of the tube 21, the increment of passage increase being more rapidly progressive between the walls 23 and 12 to the outlet 15.

In operation, sound waves from a microphone held in the socket 19 passing upwardly through the tube 21 are deflected by the triangular element 22 to travel equally 40 but on opposite sides, between the elements 23 and band 12, eventually to be directed outwardly, by the blocks 26, through the opening 15, and it will be noticed that the sound passages are constantly increasing in 45 sectional area from the socket 19 to the opening 15, while all corners or bends are so curved or filleted as to facilitate such travel.

Again reverting to the exclusive use of 50 wood, with its known results and taking into consideration the peculiar characteristics of construction described, it will be seen that a structure has been disclosed capable of fulfilling the several purposes mentioned.

Although I have described my improvements with considerable detail and with respect to certain particular forms of my invention, I do not desire to be limited to such details since many changes and modifications may well be made without departing from the spirit and scope of my invention in its broadest aspect.

Having thus described my invention, what I claim as new and desire to secure by Letters Patent, is:

65 1. A sound amplifier comprising a base, a

hollow drum shaped casing seated on the base, said casing having openings on its front wall, a socket in said base receptive of a microphone, a hollow truncated pyramid fixed in said drum with its smaller end 70 open to said socket and its larger end directed upwardly in direct communication with the chamber in the casing, means in said casing to divert sound waves from the pyramid in two substantially equal sections, 75 partitions in the casing to produce passages of constantly increasing cross sectional area, and means at the ends of said passages to expel the sound waves through the openings in the face of said casing. 80

2. A sound amplifier comprising a base, a hollow drum shaped casing seated on the base, a socket in said base receptive of a microphone, a tapered tube having its smaller terminal enclosing the end of said socket 85 and extending vertically towards the periphery of the casing to a point substantially equal to half the width of the larger end of the tube, a deflector fixed on the interior peripheral wall of the casing centrally above the tube, a substantially circular partition enclosing the upper portion of said tube between the side walls of the casing, and deflectors arranged on the rear wall of said casing between the circular partition and lower peripheral wall of the casing, the outer side wall of the casing containing openings for the emission of sound. 90

3. A sound amplifier comprising a base, a hollow cylinder seated on said base and provided with fixed ends at the rear and front, said front end being perforate, means in said base to contain a microphone, a hollow cone disposed upright in said cylinder, the smaller end of the cone being in direct communication with the microphone, means in said cylinder for bisecting the cone at larger end, and means for conducting sound waves separately in each side of the cylinder to deliver the same outwardly through the perforations in the front end, all of said means being of constantly increasing cross sectional area. 100

4. A sound amplifier comprising a base, a hollow cylinder seated on said base and provided with fixed ends at the rear and front, said front end containing an oval latticed opening in its lower portion, said base containing a recess receptive of a microphone, means in said cylinder to conduct sound 115 from the recess in the base to the upper portion of the cylinder, means to divide the sound waves, and means to conduct the divided sound waves to the opening in the front wall of the cylinder, all of the sound 120 conducting means progressively increasing in cross sectional area and wholly composed of wood. 125

5. A sound amplifier comprising a thin walled wooden drum shaped body having a 130

perforate front wall, a base on which the body rests, said base being provided with means to contain a microphone, wooden partitions forming channels in said body to receive sound from a microphone, means to divide the sound waves in their passage through the body, said partitions being subject to minute vibrations and arranged to

constantly increase the area of the channels, and means to conduct the sound waves outwardly through the perforate front wall of said body.

This specification signed and witnessed this 10th day of December, 1924.

GARROLD L. BAILEY.
